UNITED STATES PATENT OFFICE.

SALVATOR F. CAVALLI, OF UTICA, NEW YORK, ASSIGNOR OF ONE-HALF TO FELIX RUGGERO, OF WILMINGTON, DELAWARE.

VEHICLE TALKING HORN.

Application filed September 18, 1924. Serial No. 738,062.

The invention relates to vehicle horns and has for its object to provide a horn particularly adapted for motor vehicles which will simulate the human voice and speak the intention of the driver so that one may be advised when the vehicle is about to stop, or to turn to the right or to the left or otherwise be informed by speech as to the purpose of the driver and thereby avoid a collision or other fatality.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the nature of the invention.

Referring to the accompanying drawings forming a part of the specification,

Figure 1 is an elevational view illustrating the application of the invention,

Figure 2 is a sectional view,

Figure 3 is a detail view of the record and operating means,

Figure 4 is a sectional view on a plane indicated by line 4—4 of Figure 2,

Figure 5 is a sectional view on a plane indicated by line 5—5 of Figure 4,

Figure 6 is a fragmental view illustrating the switch and showing the circuit in diagram,

Figure 7 is a sectional view on a plane indicated by line 7—7 of Figure 6, looking in the direction of the arrows, and

Figure 8 is a sectional view on a plane indicated by line 8—8 of Figure 1 looking in the direction of the arrows.

Corresponding and like parts are referred to in the following description and designated in the several views of the drawings by like reference characters.

The numeral 1 denotes a horn which may be of any preferred construction and 2 designates a sound box such as usually provided for graphophones or talking machines the same including a diaphragm and a needle, the latter being indicated by the numeral 3. These parts may be mounted in any preferred way and may be constructed in any manner best adapted for the purpose. The numeral 4 denotes a rotary member which

corresponds to the rotary table of a graphophone or talking machine and this rotary member is provided with a record 5, the sound grooves 5^a being annular and concentric, as shown instead of spiral and each annular groove corresponding with a spoken signal such as "Look out", "Stop", "Turn to the right" and "Turn to the left". Any approved mechanism may be employed for rotating the member 4 and as shown an electric motor 6 has its drive shaft provided with a pinion 7 which is in mesh with cog teeth 8 of the rotary member 4. The motor 6 is included in an electric circuit which is controlled by means of a push button 9 within convenient reach of the driver, and is shown applied to the steering wheel, and when the electric button 9 is pressed the circuit is closed and the member 4 carrying the record 5 rotated.

To control the movement of the needle or stylus 3 towards and from the record disk 5, a shaft 10 is secured to button 9 and to a lever arm 11 carrying the sound box 2 and stylus 3. Lever arm 11 is pivotally and slidably mounted on a bar 12 by means of a pin 13 on said bar and longitudinal slots 14 engaging said pin, the lever 11 also having a slot 15 to receive bar 12. Bar 12 is slidably mounted in bearing 16 forming a part of the bracket 17 secured to a support 18 for horn 1. Springs 19 on bar 12, by engaging lever 11 and bearing 16, serve to return the arm 11 to its normal position after movement. 20 designates a bearing for shaft 10 on the casing of motor 6, and 21 another bearing mounted on the steering column 22, said bearing 21 carrying one member 23 of the circuit closer for the electric circuit for actuating the motor 6, said circuit being shown diagrammatically in Figure 6. 24 The other member of the circuit closer comprises an L-shaped member 24 secured to button 9, and it will be readily apparent that the projecting end of said L-shaped member 24 may function as a pointer and the member 23 may function as a dial to assist in properly adjusting the stylus to sound the signal desired. Spring 25 serves to normally hold the button 9 and shaft 10 in the position shown in Figures 1 and 6, and to return the parts to said position after actuation into signaling position when the button 9 is released. 26 designates a flexible tubu-

lar coupling on tone arm 27 to permit movement of the stylus to either side to seat in the proper record groove.

In operation it will be understood that by turning button 9 in the proper direction and then moving the button so that members 23 and 24 contact the motor 6 will be energized to rotate the record disk 5 and at the same time stylus 3 will engage the proper record groove in the disk to give the signal intended, and that the sounding of the signal will continue as long as the button 9 is held in position to engage the members 23 and 24. When button 9 is released springs 19 and 25 will react to return the parts to their original position.

It will be understood from the foregoing taken in connection with the accompanying drawings that the invention provides a horn for motor vehicles which will speak the required signal and thereby advise one as to the intention of the driver of a vehicle and said signal being spoken will not tend to cause confusion or startle the pedestrian or the driver of another vehicle and will advise in a positive manner as to the intention of the operator of the vehicle giving the signal.

What is claimed is:—

1. A talking signal, comprising a sound reproducing means adapted to be used with a record having a plurality of sound grooves arranged parallel to one another, an electric motor to actuate said record, said sound re-

producing means including a sound box, a needle associated with the sound box, an arm carrying said sound box and needle and mounted for rocking and swinging movement to engage the needle in the proper groove for enunciation of a predetermined signal, a shaft to actuate said arm slidably and rockably mounted, and circuit closing means associated with said shaft for controlling the operation of the motor.

2. A talking signal comprising a sound reproducing means adapted for use with a record having a plurality of continuous sound grooves arranged parallel with one another, an electric motor arranged to actuate said record, said sound reproducing means including a sound box, a recording needle associated with the sound box, an arm carrying said sound box and needle, a shaft slidably and rockably mounted and mounting said arm for rocking and transverse movement to position the needle in the proper groove for enunciation of a predetermined signal, a shaft operatively secured to said arm and slidably and rockably mounted, circuit closing means associated with said last mentioned shaft and controlling the electric circuit to the motor, and spring means normally tending to return the parts to their original positions after each operation of the signal.

In testimony whereof I affix my signature.

SALVATOR F. CAVALLI.
